UNITED STATES PATENT OFFICE.

DAVID FRANKLIN YOUNGBLOOD, OF SAN ANTONIO, TEXAS.

AUTOMATIC DIFFERENTIAL GAUGE.

Application filed June 14, 1923. Serial No. 645,404.

To all whom it may concern:

Be it known that I, DAVID F. YOUNGBLOOD, a citizen of the United States, residing at San Antonio, in the county of Bexar and 5 State of Texas, have invented a new and useful Automatic Differential Gauge, of which the following is a specification.

This invention relates to an automatic differential gauge, which is adapted to be 10 used in connection with a receptacle for containing fluids of a volatile or gaseous nature, such as tanks which are used for receiving and storing petroleum and the derivatives thereof. 15 The invention includes a liquid seal, which is adapted to form the only communication between the contents of the tank and the outside atmosphere, and is responsive to outside or inside pressure of a predetermined 20 amount to prevent the pressure becoming great enough to cause possible injury to the tank.

The present invention is in the nature of an improvement upon the structure disclosed 25 in my co-pending application, Serial Number 629,653, filed April 3, 1923.

One of the objects of the present invention is to modify the structure, shown in the aforesaid application, so that the same may 30 be installed within the tank without any modification in the structure of the tank, as shown and described herein. The entire gauge is secured to and supported from the underside of the man hole cover of the tank.

It is also an object of the invention to 35 provide a gauge and seal of this type in which the amount of pressure to which the gauge is responsive may be easily adjusted, and in which there will be no tendency for 40 the liquid forming the seal to blow out of the gauge when air or gas passes through the same. Since the liquid is thus prevented from blowing out of the gauge, the latter when once adjusted for a given pressure remains in this condition without requiring 45 any further attention.

The invention will be best understood from the following detailed description taken in connection with the accompanying 50 drawings, which illustrate the preferred structure thereof.

In the drawings:

Figure 1 is a side elevation of an oil tank, with a portion cut away to show the relation of the invention thereto.

Figure 2 is a vertical longitudinal section of the invention on an enlarged scale.

Figure 3 is a longitudinal section through the automatic filler.

Figures 4 and 5 are similar to Figure 2, 60 but show different modifications of the invention.

Figure 6 is a sectional view on the line 6—6 of Figure 4.

Figure 7 is a sectional view on the line 65 7—7 of Figure 5.

The invention is shown in Figure 1 as applied to an oil tank 10, having a roof 11 in the center of which is a turret 12 sufficiently large to constitute a man hole, and 70 provided with a man hole cover 13, to the underside of which the automatic gauge is secured. It will be understood that the tank is built up with air-tight seams, and normally the automatic gauge provides the only 75 communication between the interior of the tank and the outside atmosphere.

As illustrated in Figure 2, the man hole cover 13 is provided with a comparatively small opening 14, which is preferably covered by a screen 15 secured thereto by an annular flange 16. The gauge, which forms a liquid seal, is U-shaped, and in the form shown in Figure 2, the legs 17 and 18 are connected by a nipple 19 and provided with 80 clean-out openings, which are closed by plugs 20. The legs 17 and 18, which are usually about two inches in diameter, are connected at their upper ends with the small ends of the reducers 21 and 22, which serve to connect them to enlarged pipe sections 23 and 24. One of these sections, as 23, is a little longer than the other, and a flange 25 at its upper extremity serves to secure the gauge 85 to the underside of the man hole cover 13, 90 with the upper end of the pipe section 24 spaced from the cover. When the gauge is partially filled with liquid, it forms an air-tight seal which, however, will be responsive to a predetermined pressure, depending upon the amount of liquid therein, to permit the pressure to be relieved, and thereby prevent injury to the tank. The enlarged sections 23 and 24 serve to receive the overflow 95 from the liquid seal, and to permit air or gas to be blown therethrough to relieve the pressure without the possibility of any of the liquid escaping from the gauge.

One of the legs of the gauge, preferably the inner leg 18, is provided near its upper 100 110

end with a comparatively small threaded opening 26, in which is threaded a street **L** 27, and a section of small pipe 28 is threaded into the outer end of the **L** to provide an automatic filler. The angle between the section 28 and the leg 18 may be adjusted by partially rotating the **L** 27, and the outer end of the section 28, which is open, may be adjusted between a horizontal position, shown in dotted lines in Figure 1, and the full line position, in which the outer end coincides with the maximum level of the liquid seal, and thereby determine the amount of pressure which will be necessary to break the same.

In the modification illustrated in Figure 4, the gauge is formed from an integral U-shaped pipe 29 having a clean-out plug 30 at its lower end, and having also the overflow chambers 31 and 32 integrally connected to the legs and also to each other, as shown at 33. In this figure also the upper ends of the chambers 31 and 32 have reduced mouths 34 and 35 to prevent the possibility of the liquid spattering from the chambers when the seal blows. The mouth 35, in this form, is provided of the same diameter as the opening 14, and is secured to the cover 13 by a nipple 36 and flange 37, which is bolted to the flange 16.

In the form shown in Figure 5, the overflow chambers 31^a and 32^a are integrally joined together at 33, but the lower part of the gauge is separable in the manner shown in Figure 2.

In the three forms of the invention, the invention may be said to comprise an approximately U-shaped tubular member formed of two connected legs suspended from the inside of the top or cover of the receptacle by one leg, with the free upper end of the other leg open and spaced from the top or cover of the receptacle, said pipe being shaped so as to provide a liquid seal.

From the foregoing description, it will be seen that the invention provides a very simple means for attaching the automatic gauge to a tank or other receptacle without modifying the structure of the latter, and that very simple means are provided for adjusting the pressure at which the seal will be broken to prevent injury to the receptacle. Various ways are shown of constructing the liquid seal, as well as the chambers connected therewith, but they all embody the same principles in that they provide for retaining the seal at all times in its normal operative condition without permitting the liquid to escape therefrom, and they also provide means for easily cleaning the same.

It is to be understood that the various modifications are merely illustrative, and that other modifications may be devised in the shape, size and general arrangement of the parts, as long as such modifications mark

no material departure from the salient features of the invention as expressed in the claims.

What is claimed is:—

1. The combination with a receptacle, of a pipe suspended from the inside of the top of the receptacle and forming the only communication between the interior of the receptacle and the outside atmosphere, said pipe being so shaped as to provide a liquid seal. 70

2. The combination with a receptacle, of a pipe suspended entirely within the same forming the only communication between the interior of the receptacle and the outside atmosphere, said pipe being shaped so as to form a liquid seal, and a comparatively small branch pipe connected with the liquid seal and constituting an automatic filler, said pipe being angularly adjustable 85 to control the amount of liquid retained in said seal, and consequently the amount of pressure under which the seal will be broken. 80

3. The combination with a receptacle having a man hole cover, of a U-shaped tubular member suspended by one leg from the underside of the cover, the free end of the inner edge being spaced from the cover, said member forming the only communication between the interior of the receptacle and the outside atmosphere, and being normally sealed by liquid. 90

4. The combination with a receptacle having a man hole cover, of a U-shaped tubular member suspended by one leg from the underside of said cover and adapted to form a liquid seal, the free end of the inner leg being spaced from the cover, and a comparatively small branch pipe tapped into the inner leg and providing means for automatically filling the seal when the liquid in the receptacle reaches a predetermined level, said branch being angularly adjustable with respect to said inner leg. 100

5. The combination with a receptacle, of a U-shaped tubular member suspended within the receptacle and providing a liquid seal between the interior of the receptacle and the outside atmosphere, the legs of said member being enlarged above the level of the seal to form chambers for receiving and retaining the liquid blown out when the pressure exceeds the resistance of the seal. 115

6. The combination with a receptacle, of a U-shaped tubular member suspended within the receptacle and adapted to form a liquid seal therefor, a comparatively small branch pipe connected with the liquid seal and constituting an automatic filler, the legs of said U-shaped member being enlarged between the level of the seal and the ends of the member for receiving and retaining the liquid blown out when the pressure exceeds the resistance of the seal. 120

7. The combination with a receptacle having a man hole cover, of a U-shaped tubular member suspended by one leg from the underside of the cover and adapted to form a liquid seal, the free end of the inner leg being spaced from the cover, the legs of said member being enlarged above the level of the seal to form chambers for receiving and retaining the liquid blown out when the pressure exceeds the resistance of the seal.

8. The combination with a receptacle having a man hole cover, of a U-shaped tubular member suspended by one leg from the underside of the cover and adapted to form a liquid seal, the free end of the inner leg being spaced from the cover, and a comparatively small branch pipe tapped into one leg and providing means for automatically filling the seal when the liquid in the receptacle reaches a predetermined level, said branch pipe being angularly adjustable, the legs of said U-shaped member being enlarged between the normal level of the seal and the ends of the pipe to form

chambers for receiving and retaining the liquid blown out when the pressure exceeds the resistance of the seal.

9. A liquid seal for receptacles, comprising a U-shaped tubular member having its legs enlarged above the normal liquid level to form chambers for receiving and retaining the liquid blown out when the pressure exceeds the resistance of the seal.

10. A liquid seal for receptacles, comprising a U-shaped tubular member, having its legs enlarged above the normal liquid level to form chambers for receiving and retaining the liquid blown out when the pressure exceeds the resistance of the seal, and a comparatively small branch pipe tapped into one leg and angularly adjustable to vary the liquid level of the seal and the consequent pressure at which the seal blows.

In testimony, that I claim the foregoing as my own, I have hereto affixed my signature.

DAVID FRANKLIN YOUNGBLOOD.
